UNITED STATES PATENT OFFICE.

CHARLES E. HOPKINS, OF PLAINFIELD, NEW JERSEY.

SEMAUTOMATIC PLATE CASTING AND FINISHING MACHINE.

Application filed December 11, 1916, Serial No. 136,191. Renewed March 21, 1922. Serial No. 545,566.

To all whom it may concern:

Be it known that I, CHARLES E. HOPKINS, a citizen of the United States, residing at Plainfield, in the county of Union and State of New Jersey, have invented a new and useful Improved Semiautomatic Plate Casting and Finishing Machine, of which the following is a specification.

This invention relates to the manufacture of stereotype plates for use in printing machines. The principal object of it is to provide a machine of a simple and extremely reliable construction especially designed for newspaper plants having small circulation that do not require a full automatic machine.

This machine is designed to be operated by one man. It contains many new features. The mechanism is arranged so that the operator can stand at the side of the machine to position the matrix, close the casting chamber, operate the pump to make a cast, open the casting chamber and withdraw the cast plate, strip the matrix from the cast plate, inspect the plate, thereafter push the plate over guideways and align it with the finishing tools, and then start the finishing mechanism, after the completion of which the operator draws the finished plate back over the guideways and removes it from the machine by hand.

The concave back is provided with means for supporting and positioning a pouring sheet and for causing the end of said sheet to move from between the margin of the matrix and the stereotype plate cast in the box, and thereafter separate from the stereotype plate by the movement of the parts in opening the box. It is caused to travel along with the plate during the first part of the movement of the plate out of the box, and then to expand and be released from it.

The invention involves means at the bottom of the straight sides of the back for pivoting a bottom closing ring and means on the concave back for positioning said ring. The back is also provided with flexible means at the lower end for temporarily holding the matrix until the casting chamber is closed.

Horizontal rails are provided for supporting the core in the front of the back, and a rock-arm for guiding the core through

a certain motion into position within the back. Another improvement consists in the means carried by the core for moving and thereafter operating a device for locking the core in position within the back. Projecting arms are carried with the core for moving the pouring sheet into position within the back, clamping the bolster packing strips against the straight sides of the back and properly positioning the core within the back. The right end portion of the core is provided with projecting ledges at its straight sides for forming co-acting recesses and stops are located in the guideways for engaging in these recesses, and for positioning the plates relative to the finishing tools when the plate is removed from the core.

Reference is to be had to the accompanying drawings which show a preferred form of this invention and in which—

Fig. 1 is a plan of a complete machine with the core in position for delivering and the pouring sheet drawn forward out of the back;

Fig. 2 is a plan of the machine with the core in casting position, the finishing arch and gear covers being removed to show the mechanism below;

Fig. 3 is a side elevation of the machine showing the core turned partly out of the back still resting on the bottom ring, and the casting entirely withdrawn from the pouring sheet, the finishing mechanism being shown partly in section to illustrate the interior thereof;

Fig. 4 is a side elevation of the machine showing the core in central longitudinal section and also showing a part of the back in section to show the interior construction;

Fig. 5 is an enlarged view similar to a part of Fig. 4 showing the bottom of the casting box in section, and illustrating the operation of the matrix-holding catch.

Fig. 6 is a horizontal sectional view of the same near the bottom, showing the temporary matrix-holding catch in plan;

Fig. 7 is a sectional view on the line 7—7 of Fig. 4, showing how the plate is separated from the core while in horizontal position;

Fig. 8 is a transverse sectional view on the line 8—8 of Fig. 1, showing the casting mechanism in front elevation with the parts

in the same position as in Fig. 1, except that the matrix is in position and the pouring sheet is pushed back to overlap its upper edge and hold it in place;

5 Fig. 9 is a similar sectional view but showing the casting mechanism including the core in closed position;

Fig. 10 is a transverse sectional view of the closed mold with the cast plate therein;

10 Fig. 11 is a similar view showing the parts in the position taken when the core is moved partly out of the back;

Fig. 12 is a similar view showing how a bolster strip is held in place and the matrix forced back into casting position;

15 Fig. 13 is a front end view of the machine;

Fig. 14 is a face view of the cam for controlling the periodic stopping of the finishing mechanism;

20 Fig. 15 is a bottom plan view thereof, and Fig. 16 is an end view of the same.

The machine is shown supported between side frames A and B, and cross frames C and D. The casting back 10 is fixed in a vertical position between the side frames, at the rear end with its concavity facing toward the front end.

25 Each straight side of the back is provided with a vertical recess 11, in a portion of which is pivotally located a bolster packing strip 12, which is provided with an extending lip 13, which protrudes slightly within the radius of the back's concavity. These bolster packing strips are held in position so that they can rock by pins 14—14 extending into slotted holes in the said strip. The bolster packing strips are held flat against the straight sides of the back by matrix positioning fingers 20—20 sliding in angular slideways made on the sides of the back. (See Fig. 11).

30 Fast to the lower end of the vertically disposed back 10 is a half ring 16. The concavity of this half ring is made slightly smaller than the concavity of the back, the difference forming a narrow ledge 17 (see Fig. 1) upon which a pivoted bottom ring 18 seats itself, as hereafter described. This narrow ledge 17 not only forms a seat for the casting chamber bottom member or ring 18, but acts as a means for supporting and positioning a matrix M, and hold it up in casting position.

35 To prevent the matrix from slipping off the ledge 17 there is provided a spring actuated catch 19. In operation the edge of the flat margin of the matrix M is pushed down between the concavity of the back and this latch 19. When the casting chamber is closed, as hereafter described, the ring 18 swings over on the ledge 17, during which movement the ring engages the top of the latch 19 and pushes it down out of the way, whereupon the margin of the matrix M is

held between the face of the back and the aforesaid bottom ring 18.

The two slide fingers 20—20 constitute means for holding the matrix M in curved position against the concave back. These 70 are located one at each straight side of the back's concavity, and about midway of its length. These fingers 20 operate in angular slideways 27 formed on the straight sides of the back, so when advanced by hand within the radius of the back's concavity they overlap the matrix margins and force them inwardly until the matrix sets back against the concave surface of the back. (See Fig. 1).

75 The upper margin of the matrix M is held in curved position by a thin flexible metal pouring sheet 21 mounted on a cross rod 22, which operates in camways formed in brackets 23—23 fast on the top end of the 80 back 10.

80 Having described the construction of the back unit I will now explain the construction of the core unit. As is shown in several of my former inventions the core is supported 90 in front of the back's concavity, normally in horizontal position, and provided with means so it can be moved from its horizontal to a vertical position and within the back's concavity. In this case the core 30 is supported 95 by a cross yoke 31 at each end of which is mounted a roller 32, operating along tracks 29 on the top edges of the side frames A and B.

95 The core is caused to turn from a horizontal to a vertical position while being advanced toward the back, by a turning or rock arm 33, one end of which is pivoted in a bracket 34, fast to the rear end of the core, and the opposite end of which is pivoted on a cross stay 35, fast between the side frames. The turning operation continues until a seat 36 formed on the rock arm 33 engages on top of a cross stay 37, likewise fast between the side frames. When 110 the core reaches this position (shown in Fig. 3) its end enters and seats itself within the bottom ring 18. And the balance of the pivotal movement is made about the core rock arm pivot pin 38 and the pivots of the 115 bottom ring 18. During this motion the bottom ring 18 swings down to a horizontal position.

120 The complete operation of turning the core from a horizontal to a vertical position is done through a handle 40, but on the reverse operation the core is caused to start to rock to the position shown in Fig. 4 by the operator pushing down on the foot pedal 41, which is fast on a rock shaft 42, upon which 125 is fixed one end of a rock lever 43, to the loose end of which is attached one end of a vertically disposed connecting rod 44, the opposite end of which connects with the aforesaid bottom ring 18. The pedal 41 acts 130

as a counter balance to lift the bottom ring when the weight of the core is removed from it.

Locking.

Having described the construction of the back and means for supporting and operating the core I will now explain the mechanism for locking both matrix and core in casting position.

As stated the core is supported by a yoke 31. To this yoke is fixed a pair of longitudinal brackets 50 to which the core is attached by a series of space studs. Movable between the core 30 and the brackets 50, are the matrix holding and core locking bars 51—51. These bars are caused to move out beyond the convex face of the core so that a protruding lip 52 enters the recess 11, formed along the straight sides of the back's concavity, and over the bolster packing strips 12. In this position the straight margins of the matrix M are engaged between the slight projection 13 on the bolster packing strip and the side edge of the bar (see Fig. 10). In this position the inner faces of the bars 51 form the straight side walls of the casting chamber. The core is locked in casting position within the concavity of the back and the straight side margins of the matrix are held.

The means for operating the casting bars 51 consists of a pair of rock arms 53 and 54 connected by flat bars or slides 55—55, which operate in slideways 56 formed in the rear side of the casting bars. An operating handle 40 attached to the rock arm 53 serves as a means for operating the clamping and locking bars as more fully explained hereafter.

Having described the matrix and core locking means, as well as the means for positioning the matrix in the back, I will now explain how the pouring sheet is positioned and thereafter separated from the casting plate.

The pouring sheet 21 is made of thin sheet metal and curved to fit the back's concavity. The purpose of the cam slots in the brackets 23 is to cause the pouring sheet to lift upward, and withdraw its lower edge from beneath the matrix margin as the core, with a plate cast thereon, is rocked from a vertical position to the tilted position shown in Fig. 4.

The pouring sheet is forced to travel with the cast plate by longitudinal bars 24, 24 which are attached to its concave face near each straight side, imbedding in the riser 60 portion of the stereotype plate at each casting thereof, see Figs. 2 and 3.

These bars release themselves by spreading the pouring sheet when it reaches the position shown in Fig. 3, or when the pouring sheet is forced free from the cast by the

cross rod 22 reaching the end of the cam slots in brackets 23, in which position the pouring sheet is held at the released angle by stops 25 formed on the brackets 23.

Operation, closing the box.

After the operator positions a matrix in the back, he grasps the core operating handle 40, lifting up and at the same time toward the back which act causes the core to rock 75 toward and into the back's concavity, during which the projecting core positioning stops 57 formed on the core brackets 50 engage the straight sides or edges of the pouring sheet 21 causing it to move along in front of the 80 core and into casting position, whereupon the aforesaid stops come up against the upper ends of the bolster packing strips 12 and force them solidly against the back.

The operation of locking the core within 85 the back's concavity is accomplished by elevating the core rock handle 40 as follows: When the core is horizontal the operator grasps the handle 40, lifting upward and toward the back. This causes the core to 90 roll forward on its tracks during which the rock arm 33 causes the core to rock toward a vertical position, shown in Fig. 4, at which position the lower end of the core seats itself in the pivoted bottom ring 18 95 and the seat 36 on the rock arm 33 comes to rest on the cross rod 37. From this point the core turning takes place through the rock arm pivot 38 located at the bottom of the core.

During the rocking of the core about the pivot 38 the shank of a handle locking spring latch 58 attached to the yoke 31 engages against a stop 59, mounted at one side of the back. This forces the curved end of the 105 spring latch out of engagement with the handle 40 and releases same. Whereupon the operator pushes the handle upward, this turns the rock levers 53 and 54, which operate the matrix holding and core locking slide 110 bars, and force the bars out from the sides of the core and into engagement with the back as heretofore explained. (See Fig. 9).

Delivering the plate.

When a cast has been made the operator pulls down on the handle 40 thereby withdrawing the matrix holding and core locking bars 51 from engagement with the back.

The operator then steps on the foot pedal 120 41, and at the same time pulls forward on the handle 40. This causes the core to rock out of the back into the position shown in Fig. 3, during which rocking the rod 22 attached to the pouring sheet 21 travels along 125 the cam grooves in brackets 23. Owing to the angle of the cam groove the rod first moves a short way in line with the core curvature, then gradually draws the pouring sheet upward so its lower end withdraws 130

from beneath the upper flat margin of the matrix M, whereupon the rod 22 reaching the end of the cam slots the pouring sheet stops advancing and opens out its curvature sufficient to allow the bars 24-24 to free themselves from the depressions they have formed in the riser portion of the cast plate. (See Fig. 3).

The operator continuing to pull forward and downward on the handle 40, the core turns out of the back and toward the horizontal position, during which movement the plate lifters 60-60 located one on each side of the core and operating along studs fast in the core brackets 50, come into contact with the top of a cross bar 61, fast between the side frames A and B. This is so located that as the core nears its horizontal position the bar forces the plate lifters up into engagement beneath the straight edges of the stereotype plate P, cast on the core, and then pushes the plate upward and free from the convex face of the core, and upon reaching the horizontal position aligns the plate with guideways 62 and 62^a. The operator then removes the matrix M from the type face of the cast plate and pushes the cast plate along the plate lifters toward and onto the said guideways 62 and 62^a, and into position to be finished.

Positioning the cast plate longitudinally with respect to the finishing tools is done by forming recesses in the straight sides of each cast plate and locating corresponding stops. For this purpose two projecting bars 63 are located one at each side of the core, which form corresponding recesses 63^a at each straight edge, and beneath the riser portion, of the curved plate P. When the curved plate is pushed off the plate lifter and along the guideways 62-62^a, the recesses engage against stops 64, fast on the guideways which positions the plate longitudinally with respect to the finishing tools.

45

Finishing.

The means shown for finishing the stereotype plate, by separating the riser from the type face portion of the cast, beveling the curved edge from whence the riser was removed, and shaving the interior ribs consists of a revolving shaving knife and a beveling tool located upon the knife carrier, and a circular saw fast on a spindle which operates in bearings formed at one side of the knife carrier.

The rotary shaving knife carrier 70 is mounted in bearings formed on top of cross frames C and D (see Fig. 2). The usual 60 shaving knife 71 is attached to an extension of the carrier 70. The knife is of a length sufficient to engage all the ribs cast within the plate's concavity.

At the forward end of the shaving knife is 65 fixed a beveling tool 72. Opposite this bevel-

ing tool is located the circular saw 73, which is fast on the forward end of a saw spindle 74, which operates in bearings formed in the knife carrier. This saw is caused to revolve at a high rate of speed by a pinion 75, fast 70 on the opposite end of the saw spindle. The pinion 75 meshes with an intermediate gear 76 mounted loosely on a bearing formed on the knife carrier. These two gears are driven through a large gear 77, fast on one 75 end of a shaft 78 operating in bearings in the cross frames C and D. To the opposite end is made fast a bevelled gear 79 which meshes with a like gear 80, fast on the driving shaft 81.

To the forward end of the knife carrier is fast a worm gear 82 which is intermittently driven by a worm 83 loose on the driving shaft 81.

In operation the saw revolves continuously 85 at a high rate of speed, while the knife carrier makes but one revolution for each cycle of operations.

The cast plate is held in axial alignment with the knife carrier by an arch 90, whose 90 concavity is of the same radius as the curved plate to be finished. To permit the entrance of the plate within the arch one of the guideways 62^a is made movable vertically. This movement of the guideway 62^a is accomplished by a lifting mechanism consisting of two rock arms 91 fast one on each rock shaft 92. The loose ends of the rock arms carry a connecting bar 93 which operates along a surface formed on the under side of the 100 guideway 62^a.

This guideway 62^a operates in guides fast on the inner faces of the cross frames C and D.

When a plate is positioned on the guideways 62 and 62^a and against the stops 64, the operator lifts up on a rock lever 94 until the rock arms 91 are vertical, which causes the guideway 62^a to raise that side of the cast plate up into finishing position within the 110 arch 90.

As the cast plate may vary in circumference, owing to shrinkage or varying thickness in the matrix used, spring actuated plungers 95 are located in recesses formed in 115 the rock arms 91 beneath the bar 93 and the pivot bearings of the said bar are somewhat elongated to permit of the slight vertical operation necessary. (See Figs. 3 and 13).

Hand operated means for starting and automatic means for thereafter stopping after each cycle of operations are provided and consist of a sliding clutch jaw 100, mounted on the driving shaft 81. This clutch jaw is located so it will engage in corresponding jaws 125 formed on one end of the worm 83. The sliding jaw 100 is held out of engagement against the pressure of a spring 101 also mounted on the driving shaft by an anti-friction roller located in a channel in the 130

slide jaw, and mounted on the loose end of a rock arm 102, which is pivoted on the cross frame C. This rock arm carries one end of a square sliding rod 103 provided with a right angular extension 104, which engages against a lug 105 formed on a cam plate 106 fast on the inner face of the worm gear 82.

The act of lifting the guideway through the rock handle 94 pivots a rock arm 107 fast on the shaft 92 to which the handle is fixed. The loose end of the rock arm 107 engages against a collar 108 fast on the slide rod 103, and advances the same so that its right angular extension 104 moves out of engagement 15 and under the lug 105, on the cam plate 106. This frees the rock lever 102 and permits the spring 101 to advance the sliding jaw 100 into engagement with the jaws on the worm 83, whereupon the worm commences to 20 revolve with the driving shaft and carries the worm gear through one revolution. Near the end of the revolution the slide rod extension 104 is engaged by a bevel camway 109, formed in front of the stop lug 105 on the 25 cam plate 106 (see Figs. 14, 15 and 16) and is pushed backwards and in front of the advancing lug 105, which lug forces the clutch jaws out of engagement whereupon the cycle of operation ceases.

30 In operation the saw first engages the plate in the operation of separating the riser from the type face portion of the cast plate. In doing this the saw cuts a groove. As the saw nears the end of its operation the shaving knife commences its operation of smoothing off the interior ribs, thereby making the plate the proper thickness.

Simultaneously with the commencement 40 of the shaving operation the beveling tool enters the saw cut and starts the operation of beveling that end of the type face portion of the plate to the required angle.

No claim is made herein to the finishing mechanism by itself, as that forms the subject-matter of a divisional application, filed 45 September 26, 1922, Serial No. 590,607.

Although I have illustrated and described only one form of the invention, I am aware of the fact that modifications can be made 50 therein by any person skilled in the art without departing from the scope of the invention as expressed in the claims. Therefore I do not wish to be limited to all the details of construction herein shown and described, but 55 what I do claim is:—

1. In a curved stereotype plate mold, the combination of a stationary vertical concave back, a horizontal core supported in front of the back's concavity, matrix clamps carried 60 by the core, and means for turning the core into the back's concavity and for thereafter moving the matrix clamps to form the straight side walls of the casting chamber.

2. In a stereotype plate mold, the combination of a back for receiving a matrix, a 65

packing strip pivoted along the inside edge of the back and having an inwardly extending lip at its edge for engaging behind the edge of the matrix, and a matrix clamp adapted to be moved outwardly from within 70 for engaging the edge of the matrix over said lip and clamping it thereto.

3. In a mold for casting a curved stereotype printing plate, the combination with a concave back and a convex core therefor, 75 said back having an angular recess along the edge thereof and provided with a substantially radial side, of a packing strip movably mounted in said recess, and means for engaging the outer surface of the packing strip and moving it inwardly against the radial surface of the back and into casting 80 position.

4. In a mold for casting a curved stereotype printing plate, the combination with a 85 concave back and a convex core therefor, said back having an angular recess along the edge thereof and provided with a substantially radial side, of a packing strip movably mounted in said recess, means for engaging the outer surface of the packing strip and moving it inwardly against the radial surface of the back and into casting 90 position, and means for clamping the edge of the matrix against the edge of the packing strip and for closing the straight edges of the mold, said packing strip having a lip projecting into the mold cavity for engaging the outer surface of the margin of the matrix whereby when the cast plate is moved 95 out of the mold it will move the packing strip back out of operative position in said recess.

5. In a mold for casting a stereotype printing plate, the combination with a back and a core therefor, said back having a recess along the edge thereof, of a packing strip movably mounted in said recess, and means for engaging the outer surface of the packing strip and moving it inwardly against the surface of the back and into casting 105 position, said packing strip having a lip projecting into the mold cavity for engaging the outer surface of the margin of the matrix whereby when the cast plate is moved 100 out of the mold it will move the packing strip back out of operative position in said 110 recess.

6. In a stereotype plate mold, the combination with a back and core, of a movable packing strip at the edge of the back having 115 means for engaging the back of the edge of a matrix at the margin thereof, and a positioning finger outside the mold movable inwardly toward the mold cavity for engaging said packing strip and moving it into place. 120

7. In a mold for making a stereotype printing plate, the combination with a back and a core, of a packing strip pivotally mounted along the edge of the back, a slanting slide- 125 able matrix positioning finger adapted to be 130

1. moved inwardly toward the mold cavity and having a point for engaging the back of the packing strip to swing it into position against the back, and means for slidably supporting said finger.
2. In a stereotype plate making apparatus, the combination of a casting back having means for holding a matrix, a core provided with matrix clamping and core locking bars, slides in said bars, and means for operating the slides to move the bars for the purpose set forth.
3. In a stereotype plate making apparatus, the combination of a casting back, a core provided with matrix clamping and core locking bars, slide-ways in said bars, slides movable along said slide-ways, rock levers connecting with said slides for operating them, and means for rocking the said levers for the purpose set forth.
4. In a stereotype plate making apparatus, the combination of a casting back and co-acting core, matrix clamping and core locking bars located on the core, means for operating the bars, and means for locking the bar operating means.
5. In a stereotype plate making apparatus, the combination of a casting back and co-acting core, matrix clamping and core locking bars located on the core, means for operating the bars, means for locking the operating means, and means for unlocking the locking means.
6. In a curved stereotype plate making apparatus, the combination of a fixed concave casting back and a movable core, means for moving the core into the back's concavity to form a casting chamber, and means on the core for clamping it in that position, with means for locking the clamping means against operation when the core is moved out of the back's concavity.
7. In a curved stereotype plate making apparatus, the combination of a core provided with matrix clamping and core locking means, of means for locking the clamps in the open position as and for the purpose set forth.
8. In a mold for casting a stereotype printing plate, the combination with a back, of a core provided with means for clamping a matrix to the back and locking the core to the back, and means for locking said locking means in open position and for unlocking the same when the core is in closed position.
9. In a stereotype plate making apparatus, the combination of a casting back and co-acting core, matrix clamping and core locking bars located on the core, a handle for operating the bars, and a spring latch having a curved end for locking the bar operating handle.
10. In a stereotype plate making apparatus, the combination of a casting back and co-acting core, matrix clamping and core locking bars located on the core, means for opening the casting chamber, a pouring sheet located therein, means for opening the casting chamber, and means coacting with a plate cast in said chamber for causing the pouring sheet to move vertically along and simultaneously with the cast plate, as the chamber starts to open for the purpose set forth.
11. In a stereotype plate making apparatus, the combination of a casting chamber, a pouring sheet located therein, means for opening the casting chamber to deliver a cast made therein, means co-acting with the cast plate for causing the pouring sheet to travel with and at the same time move lengthwise of the cast, and means for thereafter separating the pouring sheet from the cast and holding it in position for a following casting operation.
12. In a curved stereotype plate making apparatus, having a back and a core forming a curved casting chamber therein between, the combination of a pouring sheet located in said casting chamber, means for opening the chamber, means on said pouring sheet to cause it to adhere to a cast made in the chamber, when being opened, and means for separating the pouring sheet from the cast during said opening operation.
13. In a curved stereotype plate making apparatus, the combination of a casting back, a core movable in front of the back's cavity, means on the pouring sheet for causing it to travel with a stereotype plate while on the core, and means for thereafter separating the pouring sheet from said cast.
14. In a curved stereotype plate making apparatus, the combination of a casting back and co-acting core, matrix clamping and core locking bars located on the core, a half ring located near the lower end of said back and having a ledge constituting a support for the bottom of the matrix, a pouring sheet located
15. locking bars located on the core, a handle for operating the bars, and a spring latch having a curved end for locking the bar operating handle, said handle being movable with and also independently of the core, and stationary means for detaching said curved end from the handle.
16. In a mold for casting a stereotype printing plate, the combination with a back, of a core provided with means for clamping a matrix to the back and locking the core to the back, means for locking said locking means in open position and for unlocking the same when the core is in closed position, said means comprising a spring latch, a handle for operating said locking means located in position to be engaged by the latch during a portion of its travel, and stationary means in position to engage the latch as the core moves up to closed position and disengages it from the handle.
17. In a mold for casting a stereotype printing plate, the combination with a back, of a core provided with means for clamping a matrix to the back and locking the core to the back, means for locking said locking means in open position and for unlocking the same when the core is in closed position, said means comprising a spring latch, a handle for operating said locking means located in position to be engaged by the latch during a portion of its travel, and stationary means in position to engage the latch as the core moves up to closed position and disengages it from the handle.
18. In a curved stereotype plate making apparatus, the combination of a casting chamber, a pouring sheet located therein, means for opening the casting chamber, and means coacting with a plate cast in said chamber for causing the pouring sheet to move vertically along and simultaneously with the cast plate, as the chamber starts to open for the purpose set forth.
19. In a stereotype plate making apparatus, the combination of a casting chamber, a pouring sheet located therein, means for opening the casting chamber to deliver a cast made therein, means co-acting with the cast plate for causing the pouring sheet to travel with and at the same time move lengthwise of the cast, and means for thereafter separating the pouring sheet from the cast and holding it in position for a following casting operation.
20. In a curved stereotype plate making apparatus, having a back and a core forming a curved casting chamber therein between, the combination of a pouring sheet located in said casting chamber, means for opening the chamber, means on said pouring sheet to cause it to adhere to a cast made in the chamber, when being opened, and means for separating the pouring sheet from the cast during said opening operation.
21. In a curved stereotype plate making apparatus, the combination of a casting back, a core movable in front of the back's cavity, means on the pouring sheet for causing it to travel with a stereotype plate while on the core, and means for thereafter separating the pouring sheet from said cast.
22. In a curved stereotype plate mold, the combination of a back, a half ring located near the lower end of said back and having a ledge constituting a support for the bottom of the matrix, a pouring sheet located

- near its upper end for holding the top of said matrix, and means for moving the pouring sheet away from the back's concavity.
23. In a curved stereotype plate mold, the combination of a vertical back, a bottom ring pivoted at the lower end of said back, and foot-operated means for rocking said ring for the purpose set forth.
24. In a curved stereotype plate mold, the combination of a back, a ring pivoted at the bottom of said back, and a ledge formed within the back's concavity for receiving the edge of the ring for the purpose set forth.
25. In a stereotype plate making apparatus having a back, the combination of a pivoted bottom member, a ledge formed at the end of the back upon which the bottom member can rest, and movable means for positioning a matrix upon said ledge, with means for moving the matrix positioning means out of position when the bottom member is seated on said ledge.
26. In a stereotype plate mold, the combination of a back, a horizontal core located in front of the back and movable into it, a bottom member movably located within one end of the back, and a spring-actuated catch for holding the edge of a matrix located in position to be moved out of operative position by said bottom member when it moves into casting position in the mold.
27. In a stereotype plate making apparatus, the combination of a back, a movable bottom member, a movable core, means for turning the end of the core on the bottom member, and means for operating the bottom member to turn the core away from the back.
28. In a curved stereotype plate making apparatus, the combination of a back, a bottom ring pivoted within the back's concavity, a movable core, means for turning the end of the core into the ring, and means for operating the ring to turn the core away from the back.
29. In a curved stereotype plate making apparatus, the combination of a concave back, a movable core located in front of the back's concavity, tracks for supporting the core between which it may travel, and a rock arm pivoted to the end of the core for causing the core to turn as it travels.
30. A curved stereotype plate mold having a convex core provided with means along its straight sides for forming recesses just beneath the riser as and for the purpose set forth.
31. A curved stereotype plate mold having a convex core provided with means for forming recesses within the concave side edges of a stereotype plate cast thereon and extending to the straight edge of the plate as and for the purpose set forth.
32. In a curved stereotype plate making apparatus, the combination of a convex core, a finishing mechanism, means for separating a cast plate from the core, means on the core for forming recesses along its straight edges, guideways over which the cast plate can be moved from the core into the finishing mechanism, and means on the said guideways for engaging in said recesses for limiting the motion of the core.
33. In a stereotype plate making apparatus, the combination of a core, a finishing mechanism, means on the core for forming recesses along its edges, guideways over which the cast plate can be moved from the core into the finishing mechanism, and means on the said guideways for engaging in said recesses for limiting the motion of the core.
34. In a stereotype plate making apparatus, the combination of a casting mechanism and a finishing mechanism, means for forming depressed ledges along the straight sides of a cast plate, means for turning the cast plate from the casting position and aligning it with the finishing mechanism, guideways over which the cast plate can be moved into the finishing mechanism, and means on the guideways for engaging against the depressed ledges to stop and position the plate.
35. In a curved stereotype plate making machine having a casting and a finishing mechanism, guideways over which a curved stereotype plate can be moved from the casting to the finishing mechanism, and means on the said guideways for arresting the movement of the plate in position to be finished by said finishing mechanism.
36. In a curved stereotype plate making machine, a concave back, a convex core, and means at the end of the core for forming recesses on the straight sides of a cast made between the said back and core, for the purpose set forth.
37. A curved stereotype plate making machine having a casting and a finishing mechanism, said casting mechanism having means for casting a notch in each plate, guideways over which a curved stereotype plate can be moved from the casting to the finishing mechanism, and means on the said guideways for engaging in said notch and arresting the movement of the plate in finishing position.

In testimony whereof I have hereunto affixed my signature.

CHARLES E. HOPKINS.
